UNITED STATES PATENT OFFICE

JAMES S. NEWLON, OF PICHET, OKLAHOMA

CYLINDER HEAD FOR GAS ENGINES

Application filed August 19, 1929. Serial No. 386,938.

This invention relates to improvements in a cylinder head particularly adapted for use with gas engines and the like.

An object of the invention is to provide a cylinder head which is substantially stronger, more durable and lighter than cylinder heads now in use.

Another object is to provide a cylinder head wherein the available space for the fluid cooling system is increased.

A further object is to provide a cylinder head wherein the greater portion thereof may be cast in one piece to render the head stronger, and wherein the parts which must be secured to the casting are arranged whereby they are subjected only to the pressure of the cooling medium.

Other objects and advantages of this invention will become apparent during the course of the following description.

In the drawings I have shown one embodiment of the invention. In this showing

Figure 1 is a central vertical sectional view through my cylinder head shown in position 25 on a cylinder.

Figure 2 is a sectional view taken substantially on line 2—2 of Figure 1,

Figure 3 is a plan view, and

Figure 4 is a perspective view.

Referring to the drawings the numeral 10 indicates the upper portion of a cylinder provided with a central opening 11 and a cooling chamber 12 surrounding the opening.

The present invention concerns a cylinder head indicated as a whole by the numeral 13 which is adapted to be secured to the cylinder as will be understood. The numeral 14 indicates a casting formed to provide an inverted cup-shaped firing chamber 15 therein and having a spark plug receiving opening 16 leading into the firing chamber and an intake opening 17 also leading into the firing chamber. The casting 14 includes a lower annular flange-like portion 18 provided with fluid receiving openings 19 and an upper annular portion 20 connected to the lower annular portion by a plurality of bolt receiving tubes 21. The tubes 21, annular portions 18 and 20 and the firing chamber are all cast in one piece, preferably of steel, and the bolt

openings in the tubes extend through the upper and lower annular portions whereby bolts or the like 22 may be used to secure the head to the cylinder.

Referring to Figures 1 and 4 it will be noted that the tubes 21 are slightly spaced from the outer periphery of the annular portions whereby a relatively thin substantially annular steel band 23 may be welded between the upper and lower annular portions. The upper and lower edges of the band 23 are welded to the upper and lower annular portions respectively and the ends of the band are welded to the casting adjacent the valve receiving opening 17, substantially as shown at 24 (see Fig. 2).

A cover plate indicated as a whole by the numeral 25 is adapted to be secured on the outer face of the upper annular portion 20 and is formed with a relatively thick outer annular portion 26 in which bolt receiving openings 27 are provided whereby the bolts 22 may extend therethrough when the head is secured to the cylinder. The cover plate is further formed with a relatively thin flexible inner portion or disk 28 preferably formed of cast steel, which is welded to the outer portion 26 substantially as shown in Figure 1. The disk portion is provided with a central opening 29 adapted to register with the spark plug receiving opening in the casting and a spaniel nut 30 is threaded through the opening 29 into the casting. As shown in Figure 1 the tubes 21 extend upwardly beyond the wall of the firing chamber and the portion of the casting adjacent the spark plug receiving opening extends upwardly beyond the upper extremity of the tubes whereby the cover plate will evenly contact with the casting. The space 33 between the cover plate and the firing chamber forms a portion of the cooling chamber in the head.

The operation of the device is as follows:

The bolts 22 are adapted to extend through the outer portion of the cover plate and through the casting into the cylinder in order to properly secure the head in position. When thus secured, the openings 19 in the lower annular portion of the casting will register with the cooling chamber 12 of the

cylinder to permit the cooling medium to circulate around the firing chamber. If desired a gasket 31 may be interposed between the cylinder and the head and a similar gasket 32 may be interposed between the cover plate and the outer face of the upper annular portion of the casting.

It will be noted that substantially all of the head with the exception of the band 23 and cover plate is cast in one piece thus obviating the disadvantages of prior constructions wherein the tubes are threaded into the portion of the casting surrounding the firing chamber, and also obviating the disadvantages of prior constructions wherein portions of the head subjected to pressure from within in the cylinder were formed in more than one piece. The metal band 23 and the disk 28 are the only welded portions in my construction and it will be apparent that these portions are subjected only to the pressure of the cooling medium circulating throughout the head. Obviously these welded joints will not be subjected to a great amount of pressure and the device will be materially strong and durable.

The provision of a relatively thin band 23 and a relatively thin disk 28 serves to increase the lightness of the head and yet does not sacrifice strength. Also, it will be apparent that the space throughout which the cooling medium circulates is increased in a head constructed in accordance with my invention and that greater efficiency of the engine will result from better cooling.

My cylinder head provides a construction which is easily formed, which is economical and which is capable of long life. If it is desired to remove the cover plate to gain access to the cooling chamber it is only necessary to remove the bolts 22 and the spaniel nut 30. Neither the bolts nor the nut are affected in any way by the circulation of the cooling medium and the danger of rust or corrosion to these elements is slight.

While I have described in detail the preferred embodiment of my invention it is to be understood that various mechanical changes may be made therein without departing from the spirit of the invention or the scope of the subjoined claims.

I claim:

1. A cylinder head comprising a casting formed with upper and lower annular portions having bolt receiving openings therein and being further formed with bolt receiving tubes registering with said openings, the outer peripheries of said tubes being slightly spaced from the outer peripheries of said annular portions, said casting including a firing chamber adapted to communicate with the opening in a cylinder, a spark plug receiving opening communicating with said chamber and a valve receiving opening communicating with said chamber, an annular band secured between said upper and lower

annular portions, and a cover plate arranged on the upper face of said upper annular portion and being provided with openings registering with said bolt receiving openings and said spark plug receiving opening respectively, said lower annular portion being provided with fluid receiving openings adapted to communicate with the cooling chamber of the cylinder when the head is secured thereto.

2. A cylinder head comprising a casting formed with upper and lower annular portions having bolt receiving openings therein and being further formed with bolt receiving tubes registering with said openings whereby said head may be secured to a cylinder, said tubes being slightly spaced from the outer peripheries of said annular portions, said casting including a firing chamber adapted to communicate with the opening in a cylinder, a spark plug receiving opening communicating with said chamber and a valve receiving opening communicating with said chamber, means arranged between said upper and lower annular portions for sealing the side wall of said head, and a relatively thin cover plate arranged on the outer face of said upper annular portion and being spaced from the outer wall of said firing chamber to form a cooling chamber, said plate being provided with an opening registering with said spark plug receiving opening, said lower annular portion being provided with fluid receiving openings adapted to communicate with the cooling chamber of the cylinder when the head is secured thereto.

3. A cylinder head comprising a casting formed with upper and lower annular portions having bolt receiving openings therein and being further formed with bolt receiving tubes registering with said openings whereby said head may be secured to a cylinder, said tubes being slightly spaced from the outer peripheries of said annular portions, said casting including a firing chamber adapted to communicate with the opening in a cylinder, a spark plug receiving opening communicating with said chamber, a relatively thin annular band welded between said annular portions to form a side wall for said head, a cover plate having a relatively thin portion arranged on the outer face of said upper annular portion spaced from the wall of said firing chamber and having openings registering with said bolt receiving openings, and a spaniel nut securing the central portion of said plate to said casting adjacent said spark plug receiving opening, said lower annular portion being provided with fluid receiving openings adapted to communicate with the cooling chamber of the cylinder when the head is secured thereto.

In testimony whereof I affix my signature.
JAMES S. NEWLON.
